(57) **CLAIM**

The ornamental design for a gift box insert, as shown and described.

DESCRIPTION

FIG. 1 is a back perspective view of a gift box insert embodying the design;

FIG. 2 is a front perspective view thereof;

FIG. 3 is a top plan view thereof;

FIG. 4 is a left side view thereof; and,

FIG. 5 is a right side view thereof.

The features shown in broken lines depict environmental structure only and form no part of the claimed design.
